The ornamental design for a multi-purpose handkerchief holder, as shown and described.

DESCRIPTION

FIG. 1 is a top perspective view of the multi-purpose handkerchief holder;

FIG. 2 is a bottom perspective view of the multi-purpose handkerchief holder of FIG. 1;

FIG. 3 is a top/front perspective view of the multi-purpose handkerchief holder of FIG. 1;

FIG. 4 is a top plan view of the multi-purpose handkerchief holder of FIG. 1 with a handkerchief; and,

FIG. 5 is a bottom plan view of the multiple-purpose handkerchief holder of FIG. 1 with a handkerchief.

The handkerchief depicted by broken lines illustrates environment and forms no part of the claimed design.
